US00D630918S

(12) **United States Design Patent**
Johnson et al.

(10) **Patent No.:** **US D630,918 S**
(45) **Date of Patent:** **** Jan. 18, 2011**

(54) **UNIVERSAL RATCHETING TOOL**

(75) Inventors: **Ronald L. Johnson**, San Jose, CA (US); **Robert J. Gallegos**, Fremont, CA (US); **Steven Simas Escobar**, San Jose, CA (US); **Anders Scot Hudson**, Campbell, CA (US); **Idriss Mansouri-Chafik Ruiz**, San Jose, CA (US); **Yugen Patrick Lockhart**, Palo Alto, CA (US); **Howard Allen Wilson**, Santa Clara, CA (US); **Eric M. Colton**, Torrance, CA (US)

See application file for complete search history.

We claim the ornamental design for a universal ratcheting tool, as shown and described.

(56) **References Cited**

DESCRIPTION

U.S. PATENT DOCUMENTS

244,309 A	7/1881	Rhodes
647,528 A	4/1900	Schmidt
873,363 A	12/1907	Ross
1,000,900 A	8/1911	Dorsey
1,172,656 A	2/1916	Yorgensen
1,337,769 A	4/1920	Hemming
1,398,583 A	11/1921	Bovee
1,500,852 A	7/1924	Shepard
1,530,905 A	3/1925	Nance
1,559,097 A	10/1925	Hill

FIG. 1 is a front view of the universal ratcheting tool;
FIG. 2 is a back view of the universal ratcheting tool;
FIG. 3 is a left side view of the universal ratcheting tool;
FIG. 4 is a right side view of the universal ratcheting tool;
FIG. 5 is a bottom view of the universal ratcheting tool;
FIG. 6 is a top view of the universal ratcheting tool; and,
FIG. 7 is a perspective view of the universal ratcheting tool.
